UNITED STATES PATENT OFFICE.

DUNCAN MACDONALD, OF PITTSBURGH, PENNSYLVANIA.

TUBULAR BOILER.

1,365,713.

Specification of Letters Patent. Patented Jan. 18, 1921.

Application filed September 20, 1919. Serial No. 325,139.

To all whom it may concern:

Be it known that I, DUNCAN MACDONALD, a citizen of the United States, and a resident of Pittsburgh, in the county of Allegheny and State of Pennsylvania, have made a new and useful Invention in Tubular Boilers, of which the following is a specification.

My invention relates to steam boilers and comprises a boiler of the flash type peculiarly adapted for use in steam motor vehicles. The object of my invention is to provide a water tube boiler which will be economical in first cost and in operation, will efficiently transmit the burner heat to the water it contains, and can be made in sections so as to be easily assembled in manufacture or disassembled for repairs.

My boiler is illustrated in the accompanying drawings in which Figure 1 is a plan of the whole boiler; Fig. 2 is in part an elevation and in part a vertical section through the boiler; Fig. 3 is a fragmentary plan and section of the upper headers and their connections and Fig. 4 is a horizontal section 25 through one of the vertical tubes on line 4-4 of Fig. 2.

The heating tubes 1 are arranged in a series of concentric vertical rows. The ends of tubes 1 are welded to the walls of horizontal headers 2 and 2^a. Each header is bent into a semicircle and each of its ends is welded to a hollow connection member 3. A complementary semicircular header has its ends welded to the opposite sides of 35 members 3. Each section of my boiler comprises an upper pair and a lower pair of these semicircular headers with the connections 3-3 and heating tubes 1-1. A number of such sections are assembled by 40 alining members 3-3. The sectional part of Fig. 3 illustrates the manner in which one end of each member is adapted to fit within the opposing end of another member and to form a tight joint therewith.

In the center of the boiler is a standpipe 4 about which the boiler sections are arranged. Passing through all of members 3-3 on one side of standpipe 4 and through one wall of the latter is a staybolt 5 which 45 is small enough in diameter to permit free circulation of water between it and the inner walls of members 3-3. The inner end of each staybolt 5 is secured by a spider nut 6 provided with spaces to permit the entrance 50 and exit of circulating fluids.

Tubes 1 are not perpendicular but are in-

clined. The upward inclination of tubes 1 in the outer section is from left to right and the upward inclination of those in the next section is from right to left. The direction 60 of inclination of tubes 1 in the remaining sections alternate for each section.

To increase the proportion of tube surface to the volume of water contained, I flatten each tube from a short distance above the 65 lower header to a point approximating the water level in the boiler, giving the tube between these points the shape shown in Fig. 4. In assembling these flattened tubes with the headers, I prefer to turn their flattened 70 sides horizontally so as to present their broader surface to the upwardly moving gases which rise from the burner (not shown) placed beneath the boiler. Instead of passing straight up, the gases will be diverted by the inclined tubes and forced into a tortuous path between the latter which will allow more time during the passage for the heat to be extracted and absorbed by the water. The inclined tubes also offer a 80 greater length to the heating gases than would be afforded by vertical tubes in a boiler of similar height.

The boiler water supply is connected to the standpipe 4 at 7 and the steam outlet is 85 from the standpipe 4 at 8. This outlet is through a superheating coil 9 which leads the steam to the engine to be supplied by the boiler.

The circular arrangement and the alternate inclination of the rows of water tubes 1 permit the extraction of a larger proportion of the heat than is usually obtained and result in an economical disposition of the parts which is especially valuable in 90 automobile construction. The sectional assembly enables the heating tubes and horizontal headers to be grouped in convenient units and in the event of repair or replacement it is not necessary to dismantle the 100 whole boiler to get at the defective tubes. It is possible to remove an entire section of the boiler and, by replacing the removed members 3-3 with dummy members without side openings, to retain complete circulation. While the steam then generated in the boiler will be less than the capacity of the complete boiler, it will, nevertheless, be an emergency supply which may often prove valuable.

I have shown headers 2 and 2^a as semicircular arcs which require two series of

connecting members 3—3 and provide two passages for the flow of water and steam from the headers to each other and to standpipe 4. It would be within the scope of my 5 invention to decrease the arc of the headers and insert more of such circulatory passages or to eliminate one of those shown and make each header a nearly complete circle.

I refer to the inclined tubes 1 as heating 10 tubes simply to facilitate description and reference. It will be understood that while tubes 1 provide the larger part of the heating surface, the surface of the connecting members, the standpipe, the circular headers 15 and especially the superheating coils also serve to transmit heat to fluids contained therein.

I claim:—

1. In a boiler, a central standpipe, a series 20 of concentric headers arranged about said standpipe, a second series of concentric headers arranged about said standpipe and spaced from said first series, a plurality of tubes connecting corresponding headers in 25 each of said series; each of said headers having an integral header connecting member provided with oppositely disposed openings and staybolts disposed radially of said standpipe, gripping one wall of same, pass-

ing through all of said connecting members 30 in each series of headers on that side of said standpipe and uniting said headers in a sectional, circulatory system.

2. In a boiler, a central standpipe, an upper 35 and a lower series of headers arranged in concentric circles around said standpipe, tubes connecting the upper with the lower headers, means internally connecting the upper headers together and to said standpipe and means connecting the lower headers together and to said standpipe; each of said means being removably connected to its adjacent means and to said standpipe so that any pair of corresponding upper and lower headers, with their connecting tubes may be 40 45 individually removed and replaced.

3. In a sectional boiler, upper and lower concentric headers, inclined heating tubes connecting said headers, each flattened from a point near its bottom to a point near the 50 water level to be maintained in the boiler and cylindrical throughout the remainder of its length.

In testimony whereof, I have hereunto subscribed my hand this 19th day of September, 1919.

DUNCAN MACDONALD.
